UNITED STATES PATENT OFFICE

NORMAN B. HURD, OF NEWINGTON, CONNECTICUT, ASSIGNOR TO THE AMERICAN HARDWARE CORPORATION, OF NEW BRITAIN, CONNECTICUT, A CORPORATION OF CONNECTICUT

DOOR HOLDER

Application filed April 1, 1931. Serial No. 526,889.

My invention relates to certain new and useful improvements in so called door checks and holders.

The principal object of the present invention is to provide in a door check and closer simple efficient and reliable means for holding the door ajar at any desired position and to provide therewith self-acting means to release the holder in the event of fire, whereby 10 the door closer may operate to close the door.

In the accompanying drawings, I have shown a preferred embodiment of my invention, but it should be understood that certain modifications and changes may be made without departing from the spirit of the invention or the scope of the following claims.

Generally speaking, the present invention is an improvement adapted to that type of door check, closer and holder of the type disclosed in my United States Letters Patent No. 1,595,098, of August 10, 1926.

In the accompanying drawings—

Fig. 1 is a plan view of my invention as applied to a door, the door being held open 25 by the holding mechanism;

Fig. 2 is a similar view showing the door closed, the holding mechanism having been released;

Fig. 3 is an end elevation of certain details; 30 Fig. 4 is a relatively enlarged longitudinal section of certain parts in one position;

Fig. 5 is a similar view showing certain parts in a different position;

Fig. 6 is a view of the under-side of the 35 parts as shown in Fig. 4;

Fig. 7 is a cross-section on the line 7—7 of Fig. 6.

10 represents the housing of a door check and closing mechanism of any suitable construction mounted on the door 11 hinged at 12 on the door casing 13. 14 represents a shaft suitably connected with the closing and checking mechanism within the housing. 10 15 is an arm fixed on the end of the shaft 14. 15 is an arm pivoted to the outer end of the arm 15 is another arm 16 pivotally connected at 16^a to the door casing 13. The arm 16 may be telescopically adjustable in any suitable way. The hinged connection between the 50 arms 15—16 is so constructed that when the

door has been opened to a predetermined degree, for example as shown in Fig. 1, these hinged ends will jam so as to hold the door in said open position. A preferred form of the construction by which this object is attained 55 is shown in the drawings, wherein it will be seen that the arm 16 is provided with an annular head which forms a cam ring 17. This ring is mounted to concentrically rotate on the upstanding hub of the head-piece 15^a 60

at the end of the arm 15. 18 is a bearing disk which overstands the cam ring 17. 19 is a key, one end of which rests in a groove in the upper face of the hub portion of the head-piece 15^a, the other end extending into a 65 groove in the under-side of the bearing disk 18, as best seen in Figs. 4 and 5. By means of this key, the parts 15^a and 18 cannot turn independently, but the cam ring 17 may rotate between them when unrestrained. The cam 70 ring 17 is somewhat tapered so as to be thinner on one side than on the other whereby it will effect a camming or a wedging action between the parts 15^a and 18. In order that it shall so act, I locate a bolt 20, by which the several 75 parts are held in assembled position, eccentrically of the parts 15^a, 17, and 18 with sufficient clearance around the bore of the bolt passage to permit said parts not only to rotate 80 relatively to each other in the manner described, but also to rock relatively to each other. 21 is an adjusting nut on the bolt 20, and 22 is a check nut to hold the nut 21 when the proper adjustment has been effected. Between the inner side of the adjusting nut 85 21 and the adjacent under-side of the part 15^a, I locate the end of a rocking bar 23, the end of said bar having a passage for the bolt 20. The adjusting nut 21 has a collar 21^a which extends up on the screw threaded part of the bolt 20 so as to extend into the passage through the bar 23 so that said bar will not bruise the screw threads of the bolt 20. The end of the bar 23 which surrounds the collar 21^a is preferably tapered outwardly so as to 90 be thinner at the outer edge, as seen in Figs. 4 and 5. The other end of the bar 23 is held by a screw bolt 24 and nut 25 to the arm 15. Manifestly, when the bar 23 is drawn up 95 tightly into the position shown in Fig. 4 and 100

when the bolt 20 is inserted and the adjusting nut 21 is drawn up, its position will determine the degree of freedom between the parts 15^a, 17 and 18 so that the device may be adjusted to jam at any desired angle of the two arms 15—16 relatively to each other. To adjust the parts so that the door will be held ajar at any particular angle, the door is opened to the desired position, the adjusting nut 21 is then turned up with sufficient tightness to clamp the parts 15^a, 17 and 18 together with sufficient snugness to resist the power of the mechanical door closer to close the door, whereupon the door will be held ajar at that particular angle, and this angle may be varied at will by simply adjusting the nut 21 to the proper position.

I have thus far described one form of door check, closer and holder to which my invention applies, the said invention as originally pointed out relating particularly to a means for releasing the holder so that, in the event of fire, the closer mechanism may mechanically close the door. This construction comprises a pair of scissor-like lever arms 26—27 pivoted together at 28 on the arm 15. The extreme rear or inner ends of the arms 26—27 are offset to form stops 26^a—27^a as best seen in Figs. 4 to 6, so that when the arms 26—27 are unrestrained it will check the opening of the arms 26—27 and prevent excessive movement, as shown in Fig. 2, when they have opened sufficiently far to accomplish their intended purpose. Each lever arm 26—27 is provided with a notch such as indicated at 29 in Fig. 5, and these notches are located opposite to each other and are beveled so as to fit under the head of the screw bolt 24, which head is also preferably beveled or tapered on the under-side. 30 is a fusible link by which the outer ends of the arms 26—27 are connected, preferably through the medium of adjustable hooks 31—32. The shank of each of these hooks is slotted to slip over the end of the link to which it is to be attached, and these links are provided respectively with an adjusting screw 33—34 which enters the back of the slot in each shank and engages in a notch in the adjacent edge of the scissors arm on which it is mounted. To assemble the parts ready for operation, the adjusting screw 21 is backed off sufficiently far to permit the bar 23 to be moved up into the position shown in Fig. 4 so that it will rest tightly against the under-side of the arm 15. The screw bolt 24 is then raised up to a position where the under-side of the head of the screw will be engaged in the notched portion of the scissors members 26—27. The fusible link 30 is then applied so as to connect the two ends of the scissors arms 26—27 as plainly shown in Fig. 6. In this position, the beveled notches extend under the head of the screw 24 so that the nut 25 may then be tightened up to hold the bar 23 against the

lower side of the arm 15 as shown in Fig. 4. When in this position, the door may be opened to the position that it is intended to be held in by the holder mechanism, and the adjusting nut 21 is turned up until the several parts are bound together tightly enough to jam and prevent the door from closing under the influence of the closer. With the mechanism thus set, the door may be manually opened to such a degree that the hinged connection between the arms 15—16 will be caused to bind and hold the door ajar. The door will necessarily stay ajar until it is either released manually or automatically. Obviously, the friction may be overcome by applying manual pressure to the door in the right direction to close it, but if, in the absence of any attendant, a fire should occur in the vicinity of the door, the heat would melt the fusible link 30, whereupon the arms 26—27 would be forced apart by the wedging action of the tapered under-side of the head of the screw 24, since, obviously, whenever the arms 15—16 are opened to a point where the parts 15^a, 17, and 18 jam, an added tension will be put upon the bar 23 and the screw 24. Thus, the moment the scissor arms 26—27 open or spread, the action of the bar 23 will be to rock from the position shown in Fig. 4 to that shown in Fig. 5 wherein tension will be taken off between the members 15^a, 17, and 18, and the mechanical door closer mechanism will then operate to instantly close the door. It will be noted that it is the cam ring that causes the two arms to bind together to hold the door in open position when the lever arms have been moved apart to a predetermined angle, whereas the bolt 20 serves as an adjusting means to vary the position at which the binding action caused by the cam ring occurs, while at the same time serving as a means for holding the parts in assembled relation. It will also be noted that the slots in the shank of the hooks 31—32 are sufficiently long to permit the ends of the lever arms 26—27 to be adjusted to and from said shanks, whereby variations in the length of the fusible link may be compensated.

I claim:

1. A door holder comprising, two arms pivotally connected together and including a cam ring to frictionally jam said pivotal connection when said arms are moved to a predetermined angle, to hold a door in open position, with means to release the frictional tension between said cam ring and associated parts in case of fire, whereby the door may close, said releasing means including a pair of scissor levers normally engaging between them one of the parts of the pivotal connection to hold the same normally in a fixed operative position and to release the same from its operative position in case of fire,

with a fusible element for holding said levers in said operative position.

2. A door holder comprising, two arms pivotally connected together and including a cam ring to frictionally jam said pivotal connection when said arms are moved to a predetermined angle, to hold a door in open position, with means to release the frictional tension between said cam ring and associated parts in case of fire, whereby the door may close, said releasing means including a pair of scissor levers normally engaging between them one of the parts of the pivotal connection to hold the same normally in a fixed operative position and to release the same from its operative position in case of fire, with a fusible element for holding said levers in said operative position, and with means for varying the tension on said fusible element.

3. A door holder comprising two arms pivotally connected together and including a cam ring connected to the end of one of said arms and rotatable therewith, to normally frictionally jam the pivotal connection in one predetermined position, and also including a bolt, a rocking bar coacting with the latter in any predetermined position of adjustment whereby the turning of the cam ring to its said one predetermined position will jam said connection, and a pair of scissor levers normally for holding said rocking bar in normal operation, fusible means associated with said scissor levers to release the same in case of fire and free said rocking bar and the frictional tension of the cam ring to permit the door to close.

4. A door holder comprising two arms pivotally connected together, including a cam ring to frictionally jam said pivotal connection when the said arms are moved to a predetermined angle to hold a door in open position, said pivotal connection also including a rocking bar, and a bolt for holding together the several parts of said pivotal connection, a screw bolt for holding said rocking bar normally in operative position, a pivoted arm operating to hold said screw bolt in position to hold said rocking bar in said operative position, and fusible means to free said pivoted arm to in turn free said screw bolt to in turn free the rocking bar and thereby the frictional tension in the pivotal connection for the first-mentioned arms.

5. A door holder comprising, two arms pivotally connected together and including a cam ring to frictionally jam said pivotal connection when said arms are moved to a predetermined angle, to hold a door in open position, and also including a rocking bar, a bolt for holding together the several parts of said pivotal connection, a device for holding the rocking bar normally in operative position, a pivot lever operating to hold said device in position to hold said rocking bar in

operative position, and a fusible means to free said lever arm, to in turn free said device, to in turn free the rocking bar and thereby release the frictional tension in the pivotal connection for the first-mentioned lever arms.
